CLAIM

The ornamental design for a glass house, as shown and described.

DESCRIPTION

FIG. 1 is a front elevation view of a glass house showing the new design;

FIG. 2 is a back elevation view thereof;

FIG. 3 is a left-side elevation view thereof;

FIG. 4 is a right-side elevation view thereof;

FIG. 5 is a top plan view thereof;

FIG. 6 is a bottom plan view thereof;

FIG. 7 is a perspective view thereof;

FIG. 8 is another perspective view thereof;

FIG. 9 is a perspective view thereof with the door of the glass house shown in an open position;

FIG. 10 is an enlarged perspective view taken at 7 in FIG. 7;

FIG. 11 is an enlarged perspective view taken at 11 in FIG. 8; and,

FIG. 12 is an enlarged perspective view taken at 12 in FIG. 8.

The equal-length broken lines depict portions of the glass house that form no part of the claimed design.

The dash-dot lines in FIG. 7, FIG. 8, FIG. 10, FIG. 11 and FIG. 12 illustrate the boundaries of the enlarged view indicators and form no part of the claimed design.
